UNITED STATES PATENT OFFICE.

ALBERT COOK, OF HOLYOKE, MASSACHUSETTS.

BAND-TYING GAUGE.

Application filed December 10, 1921. Serial No. 521,435.

To all whom it may concern:

Be it known that I, ALBERT COOK, a citizen of the United States, and resident of Holyoke, in the county of Hampden and State of Massachusetts, have invented certain new and useful Improvements in Band-Tying Gauges, of which the following is a specification.

This invention relates to improvements in gauges for use in tying driving bands, of band-driven machines, with a regulated tension, the improved device being especially adapted for use in tying the spindle driving bands of spinning or twisting frames.

The invention has for its object to provide a simple and durable device of the character set forth so constructed as to decrease the labor and time required in tying bands.

In the drawings, Fig. 1 is a side elevation of the device attached to a spindle bearing and spindle rail ready for use;

Fig. 2 a similar view showing the pivoted tension controlling member in locked position;

Fig. 3 a vertical sectional view of the device on the line 3—3 of Fig. 4, the band throw-off lever being shown tripped;

Fig. 4 a plan view of the device, the parts being in the position shown in Fig. 2, the whorl guards and the spindle bearing being shown in section;

Figs. 5 and 6 end elevations respectively of the outer and inner faces of the device;

Fig. 7 a detail sectional view showing the device for locking the tension regulating member; and

Figs. 8, 9 and 10 diagrammatic views illustrating the tying of a band.

The device comprises an attachment and positioning member 1 which is slotted at its lower end and provided with lugs 2 at the opposite vertical sides of the slot. Between these lugs the lower end of a swinging tension-regulating member 3 is pivotally held by a suitable pivot pin 4. A horizontal bracket 5 is carried by the member 1 near its lower end, said socket being on the opposite side of the member 1 from the tension member and adapted to extend under the spindle rail. The bracket 5 is formed with two lugs 6 which extend through the slot in the member 1 and are secured in position by the pivot pin 4. The lugs 6 snugly

fit the slot so that there can be no free up-and-down-movement of the bracket 5 independently of the member 1. The bracket 5 is provided with an elongated aperture 7 adapted to receive the lower end of a spindle bearing or bolster 8 which depends from rail 9 of the spinning frame. The aperture 7 is preferably of the same width transversely as the diameter of the spindle bearing, but has considerably greater length to facilitate its engagement with the bearing when the device is in position for use.

The tension member 3 is formed with an extension or abutment 10, at its lower end which is adapted to engage the upper wall of the slot in the member 1 between the lugs 6 and to serve as a stop to limit the outward and downward swinging movement of the tension member away from the support or positioning member 1. The tension member 3 is mounted on the pivot 4 between the lugs 6, as clearly shown in Fig. 5. The tension member 3 is normally swung away from the support or positioning member 1, to the limit of the movement permitted by the lug 10, by a tension-regulating spring 11. One end of this spring is confined in a socket 12 formed in the member 1, and the other end thereof is confined in a socket 13 formed in an externally threaded plug or nut 14 screwed into the outer end of a cylindrical bore or passage 15 extending through extension member 3, said bore or passage being formed in a cylindrical enlargement 16 of said member. The nut 14 is provided with an interior angular, longitudinally-extending projection 17 which is adapted to be engaged by a wrench for adjusting the nut to vary the tension of the spring 11. Said wrench must be inserted through an aperture in the member 1 and longitudinally through the spring and passage 15.

The member 1 is provided at its upper end with an integral bracket 26 which is designed to project rearwardly or inwardly over the spindle rail when the device is in operative position. The bracket 26 is cut away at its free end to form a notch or recess 27 adapted to bear against the spindle bearing 28 between the rail 9 and the spindle whorl 29 and close to the said whorl. Secured to the upper surface of the bracket 26 is a plate 30, the free end of said plate being cut out or notched as at 31 to fit

around and engage the spindle bearing 28, said notch being of such size as to accurately center the bracket 26 on the spindle bearing directly below the spindle whorl. 5 The plate 30 is secured to the upper surface of the bracket 26 by screws 32; and its free end is formed with the upwardly and inwardly extending guard lugs 33 which fit over the lower flange of the whorl at diametrically opposite points. 10 The purpose of these guard lugs is to prevent the band slipping down under the whorl during the tying operation and also when the tied band is released from the tying device and 15 connected to the whorl. These guard fingers quite closely embrace the lower flange of the whorl and prevent the spindle being lifted in its bearing so that the whorl is held in a substantially fixed vertical position 20 with respect to the tying device.

The upper surface of the bracket 26 is cut away to form the horizontal shoulders 35 directly below the plate 30. Secured to each side of the bracket 26 by means of 25 screws 36 and bearing on the shoulders 35, is a spring side arm 37. The free ends of these side arms are bent inwardly toward each other and then back upon themselves to form triangular gripping jaws 38. 30 These jaws are adapted to be forced over the spindle bearing and to yieldingly engage it in order to hold the tying device in position.

The member 3 is provided at its upper 35 end with an arm 39, the free end of which is beveled outwardly and downwardly to form a cam surface 41. This cam surface is adapted to engage and ride over the upper end of a vertically slidable latch 42 and 40 to depress said latch against the pressure of springs 43 when the member 3 is swung toward the member 1. The arm 39 is provided with a locking shoulder 44 which is adapted to snap back of the latch bar 42 to 45 lock the tension member 3 against movement after the same is swung a predetermined distance toward the spindle. The latch 42 is confined in a channel formed in the member 1, and the springs 43 are 50 mounted in sockets formed in said member, as shown in Fig. 7. A pin 45 mounted in member 1 and engaging in a slot 46 in the latch bar 42 serves to limit the movement of said bar. The latch bar at its upper end 55 is provided with two outwardly extending finger pieces 47, one on each side of the arm 39, and said finger pieces are adapted to be depressed by the operator when he desires to release the tension member from 60 the latch 42.

The arm 39 is formed broad and flat on its upper surface; and at its free or inner end, that is to say, the end that is brought close to the spindle whorl in the act of 65 tying the band, it is provided with two up-

wardly and inwardly projecting guide hooks 48, one of said hooks being arranged at each side edge of the said broad flat surface, so that said hooks are separated from each other a considerable distance 70 and are on opposite sides of a vertical plane passing through the center of the tension member. These hooks face toward the whorl when the device is in position on the spindle rail and are so positioned upon the 75 tension member that when said member is in its latched position said lugs will lie close to the whorl on opposite sides of a vertical plane drawn through the center of the spindle and through the center of the 80 tension member. These lugs are adapted to engage the two members of the looped band and to maintain said band in engagement with the whorl.

The arm 39 is also formed with two upwardly extending outwardly or forwardly facing (toward the operator) tension hooks 49, one of said hooks being arranged at each side edge of the broad upper surface of the tension member so that said hooks 90 are directly in line with the guide hooks 48 on each side of said member. The hooks 49 are separated from each other a considerable distance so that the knotted end of the looped band may lie between them and 95 also between the guide hooks, as shown in Fig. 9.

In Figs. 8, 9 and 10 the operation of the tension and guiding hooks is illustrated. 100 Spindle driving bands are usually formed of two strands twisted together. A loop is formed at one end of the band and at the other end the two strands are separated. One of these separated ends is passed 105 through the said loop in one direction and the other is passed through the loop in the opposite direction when it is desired to tie the band to the spindle. As shown in Fig. 8, the separated strands, after they have been passed through the loop in the end 110 of the band, are passed outwardly in opposite directions under the tension hooks 49. Obviously, this holds the partly tied band on the top of the tension member and 115 maintains the two members of the band in the guide hooks 48. Any form of tension device may be employed to engage the separated strands, for the purpose described.

The operation of tying the band is as follows:

The lower end of the spindle bearing 8 is 120 engaged in the aperture 7 of the bracket 5 and the member 1 is then swung upwardly to bring its inner face into engagement with the spindle rail 9 and to cause the spring 125 jaws 38 to engage the spring bearing 37. The recess 27 of the bracket 26 and the recess 31 of the plate 30 receive the spindle bearing; and all of these parts serve to center the member 1 properly and to hold it 130

against the spindle rail. The guard lugs 33 fit over the lower flange of the spindle whorl. The tension member is free of the latch 42 and the spring 11 forces it forwardly, that is to say, toward the operator, and downwardly to the limit of its movement. The lug 10 serves as a limit stop. The spindle driving band is then passed around the drive pulley or drum and on opposite sides of the spindle whorl and its ends are brought together in front of the spindle whorl and between the guide hooks 48. One strand of the band is passed through the end loop of the band in one direction and the other strand is passed through said loop in the opposite direction. These separated strands are then passed laterally in opposite directions under the tension hooks 49. The operator then pulls the strands laterally in opposite directions with the strands bearing and riding on the tension hooks. This causes the tension member to swing upwardly toward the spindle rail. It will be understood that as the strain is put on the separated strands they are pulled out or unravelled from the main body of the band. This shortens the band and puts a strain on the tension hooks which forces the tension member upwardly and toward the spindle rail and the guide hooks guide the band and maintain it on the whorl. The amount of strain required to throw the tension member to its latched position will depend upon the adjustment of the spring 11 and consequently this will regulate the amount of tension on the tied band. When the band has been contracted sufficiently to place the desired amount of tension on the tension member, said member will have been swung upwardly to its latched position, as illustrated in Figs. 2, 3 and 9. This takes the tension of spring 11 off the band and by releasing the tension on the separated strands the partly knotted portion of the band will move into the whorl. The tying of the band may then be completed by tying together the two separated strands and the completely tied band will be in direct engagement with the whorl, as shown in Fig. 10. The guard lugs 33 prevent the band drawing down under the whorl during the tying operation and also prevent the whorl and spindle being accidentally lifted during the tying operation. When the tying operation is completed the latch plate 42 is depressed and the tension member thereby released. The device may then be quickly removed from the spindle. Of course, the device may be released from the spindle without releasing the tension member, but it is the usual practice to release the tension member before detaching the device from the spindle rail.

The invention is especially adapted for use in connection with spindle whorls of large diameter; and the device is so designed

that the final tying of the band is done with the band in direct engagement with the whorl.

What I claim is:

1. A band tying gauge comprising an attachment member, means to detachably connect said member to a spindle support, and a movable band tensioning member yieldingly held to the attachment member and having a pair of hooks formed on the tension member and between which the knot in the band may be formed and against which the free ends of the partially tied strands may be pulled in opposite directions to place the desired tension on the band to contract it and move the tension member toward the spindle. 70

2. A band tying gauge comprising an attachment member, means to detachably connect said member to a spindle support, and a movable band tensioning member yieldingly held to the attachment member and having two separated tension devices on the upper end of the tension member and between which the knot in the band may be formed and against which the free ends of the partially tied strands may be pulled in opposite directions to place the desired tension on the band to contract it and move the tension member toward the spindle. 80

3. A band tying gauge comprising an attachment member, means to detachably connect said member to a spindle support, and a movable band tensioning member yieldingly held to the attachment member and having two upwardly extending separated tension devices on the upper end of the tension member and between which the knot in the band may be formed and against which the free ends of the partially tied strands may be pulled in opposite directions to place the desired tension on the band to move the tension member toward the spindle. 95

4. A band tying gauge comprising an attachment member, means to detachably connect said member to a spindle support, and a movable band tensioning member yieldingly held to the attachment member and having two upwardly extending separated tension devices formed integral with the upper end of the tension member and between which the knot in the band may be formed and against which the free ends of the partially tied strands may be pulled in opposite directions to place the desired tension on the band to contract it and move the tension member toward the spindle. 110

5. A band tying gauge comprising an attachment member, means to detachably connect said member to a spindle support, and a movable band tensioning member yieldingly held to the attachment member and having two separated tension hooks rigidly connected to the upper end of the tension 125

member and projecting forwardly toward the operator and between which the knot in the band may be formed and against which the free ends of the partially tied strands may be pulled in opposite directions to place the desired tension on the band to contract it and move the tension member toward the spindle.

6. A band tying gauge comprising an attachment member, means to detachably connect said member to a spindle support, a band tensioning member pivotally mounted on the attachment member and swinging upwardly and inwardly toward the attachment member, a spring forcing the tension member away from the attachment member, the said tension member having two separated tension hooks rigidly connected to its upper end and projecting away from the attachment member and between which the knot in the band is formed and against which the free ends of the partially tied strands are pulled to place the desired tension on the band and to contract it and swing the tension member toward the spindle, and a latch to lock the tension member when it has reached a predetermined position.

7. A band tying gauge comprising an attachment member, means to detachably connect said member to a spindle support, a band tensioning member pivotally mounted on the attachment member and swinging upwardly and inwardly toward the attachment member, a spring forcing the tension member away from the attachment member, the said tensioning member having two separated tension devices on its upper end and between which the knot in the band is formed and against which the free ends of the partially tied strands are pulled to place the desired tension on the band to contract it and swing the tension member toward the spindle, and a latch to lock the tension member when it has reached a predetermined position.

8. A band tying gauge comprising an attachment member, means to detachably connect said member to a spindle support, a band tensioning member pivotally mounted on the attachment member and swinging upwardly and inwardly toward the attachment member, a spring forcing the tension member away from the attachment member, the said tension member having two separated tension hooks rigidly connected to its upper end and projecting away from the attachment member and between which the knot in the band is formed and against which the free ends of the partially tied strands are pulled to place the desired tension on the band to contract it and swing the tension member toward the spindle, a latch to lock the tension member when it has reached a predetermined position, and a

pair of guard lugs carried by the attachment member and adapted to engage over the lower flange of the spindle whorl.

9. A band tying gauge comprising an attachment member, means to detachably connect said member to a spindle support, a band tensioning member pivotally mounted on the attachment member and swinging upwardly and inwardly toward the attachment member, a spring forcing the tension member away from the attachment member, the said tension member having two separated tension hooks rigidly connected to its upper end and projecting away from the attachment member and between which the knot in the band is formed and against which the free ends of the partially tied strands are pulled to place the desired tension on the band and to swing the tension member toward the spindle, a latch to lock the tension member when it has reached a predetermined position, and a pair of inwardly facing guide hooks carried by the tension member at the upper inner end thereof and adapted to be engaged by the band between the knot and the whorl in the operation of tying the band and to guide the band to the whorl when the tension member is swung inwardly over the spindle rail.

10. A band tying gauge comprising an attachment member, means to detachably connect said member to a spindle support, and a movable band tensioning member yielding held to the attachment member and having a tension device carried by the tension member and against which one of the free ends of the partially tied strands may be pulled to place the desired tension on the band to contract it and to move the tension member toward the spindle, the said tensioning member being adapted to permit the partially tied band to pass freely to the spindle whorl when the tensioning member has completed its movement and the tension upon the said free end of the band is relieved.

11. A band tying gauge comprising an attachment member, means to detachably connect said member to a spindle support, and a movable band tensioning member yielding held to the attachment member and having a tension device carried by the tension member and against which the free ends of the partially tied strands may be pulled in opposite directions to place the desired tension on the band to contract it and to move the tension member toward the spindle, the said tensioning member being adapted to permit the partially tied band to pass freely to the spindle whorl when the tensioning member has completed its movement and the tension upon the said free ends of the band is relieved.

12. A band tying gauge comprising an attachment member, means to detachably con-

- nect said member to a spindle support, a band tensioning member pivotally mounted on the attachment member and swinging upwardly and inwardly toward the attachment member, and a spring forcing the tension member away from the attachment member, the said tension member having at its upper end a tension device having two separated bearing surfaces against which the free ends of the partially tied strands may be pulled in opposite directions to place the desired tension on the band to move the tension member toward the spindle, the said tension member providing a free unobstructed passage way to permit the partially tied band to pass freely to the spindle whorl when the tension member has completed its movement and the tension upon the said free ends of the band is relieved.
13. A band tying gauge comprising an attachment member, means to detachably con-
- nect said member to a spindle support, and a movable band tensioning member yieldingly held to the attachment member and having two upwardly extending separated tension devices at its upper end upon which devices the free ends of the partially tied strands may be pulled in opposite directions to place the desired tension on the band to contract it and move the tension member toward the spindle, the said tension member being formed with a flat surface extending from a point between the bases of said tensioning devices to the edge of the tensioning member adjacent the spindle whorl, the said surface providing a path over which the partially tied band may pass freely to the whorl when the tension upon the free ends of the band is relieved.
- In testimony whereof I hereunto affix my signature.

ALBERT COOK.
